UNITED STATES PATENT OFFICE.

HARRY R. WALKER, OF GALATIA, ILLINOIS.

INTENSIFIER.

1,344,528.

Specification of Letters Patent. Patented June 22, 1920.

Application filed August 23, 1919. Serial No. 319,325.

To all whom it may concern:

Be it known that I, HARRY R. WALKER, a citizen of the United States, residing at Galatia, in the county of Salina and State 5 of Illinois, have invented new and useful Improvements in Intensifiers, of which the following is a specification.

This invention relates to intensifiers, for the ignition systems of internal combustion engines, for the purpose of increasing the strength of the spark at the spark plug electrodes, especially when the latter are covered with a coating of carbon deposits or oil.

15 Various means have heretofore been employed for accomplishing this result, usually, by securing an intensifier to the spark plug terminal. This is objectionable in that these intensifiers are frequently expensive and 20 easily become broken owing to their exposed position when the hood of the automobile is raised.

The present invention aims to overcome these disadvantages by providing an exceedingly inexpensive attachment, which 25 may be easily and quickly secured within a coil box, such as is used upon automobiles of the Ford type, the said attachment being in the nature of an insulated strip positioned 30 between the coil unit contact and the adjacent spring contact, to separate the same and cause the current to jump the space so provided and thereby increase or intensify the strength of the spark.

35 Other objects and advantages of the invention will appear as the following description is read in connection with the accompanying drawings:

In the drawings:—
40 Figure 1 is a sectional view through a coil box showing the application of the invention.

Fig. 2 is a detail perspective of the invention *per se*.

45 Referring to the drawings in detail, wherein like characters of reference denote corresponding parts, the reference character 10 denotes a coil box of the usual or any preferred construction, within which is 50 housed a coil unit 11. Connected to the coil box is a terminal 12, to which there is designed to be connected the primary circuit of the ignition system of an internal combustion engine. The terminal 12 is held in 55 position by means of a bolt 13, which has

secured thereon within the coil box a spring contact 14, which is adapted to engage a fixed contact 15 carried by the coil unit 11. This provides for a connection between the coil unit and the primary circuit, while the 60 secondary circuit is similarly connected by means of a terminal 16, a spring contact 17 and a fixed contact 18. All of the foregoing is of the ordinary construction and forms no part of the present invention. 65

The invention resides in the provision of means for separating one of the spring contacts and the fixed contact, so as to cause the current to jump the gap formed by the separation of these contacts. For this purpose there is provided a strip 19, which is preferably formed of fiber or other insulating material. One end of this strip is provided with an opening 20, which is slightly offset from the longitudinal center of the 70 strip and is adapted to receive the bolt 13, which holds the terminal 12 of the primary circuit to the coil box. The strip 19 is positioned beneath the spring contact 14, so that the latter will still engage the fixed contact 15 of the coil unit. The lower end of the strip 19 is provided with spaced apertures 21 and this end of the strip is interposed between the spring contact 17 and the fixed contact 18 of the secondary circuit, the 75 apertures 21 being disposed at the point of separation of the said contacts. This position of the strip 19 separates the contacts 17 and 18, so as to provide a gap which is 80 jumped by the current passing through the secondary circuit and builds up or increases the strength of the same. This causes the plug electrodes to spark, even though they are fouled by the accumulation of carbon 85 or oil. 90

The invention is susceptible of various changes in its form, proportions and minor details of construction and the right is herein reserved to make such changes as properly fall within the scope of the claims 100 hereto appended.

Having thus described my invention what I claim as new is:—

1. The combination with a spark coil unit having a fixed contact and a spring contact, 105 of an insulated element interposed between said contacts to space the latter apart to provide a gap.

2. The combination with a spark coil unit having a fixed contact and a spring contact, 110

of means interposed between the said contacts to space the latter apart to provide a gap.

3. The combination with a spark coil unit having a fixed contact and a spring contact, of a perforated insulated element interposed between said contacts to space the latter apart and to provide a gap through said perforations.

- 10 4. The combination with a spark coil hav-

ing spaced fixed contacts and removable spring contacts associated therewith, of a strip of insulating material secured beneath one of the spring contacts and extending between the other spring contact and the adjacent fixed contacts and having openings therein to provide a gap. 15

In testimony whereof I affix my signature.

HARRY R. WALKER.
